UNITED STATES PATENT OFFICE.

GEORGES COULON, OF PARIS, FRANCE.

SYSTEM OF SECURING VIGNOLES RAILS TO TRANSVERSE OR LONGITUDINAL SLEEPERS.

SPECIFICATION forming part of Letters Patent No. 561,968, dated June 16, 1896.

Application filed April 16, 1895. Serial No. 545,948. (No model.) Patented in Belgium October 22, 1894, No. 112,388.

To all whom it may concern:

Be it known that I, GEORGES COULON, a citizen of the Republic of France, residing at Paris, France, have invented a certain new and useful System of Securing Vignoles Rails to Transverse or Longitudinal Sleepers, (for which I have obtained Letters Patent in Belgium, No. 112,388, dated October 22, 1894,) of which the following is a specification.

10 Two kinds of appliances are used to secure Vignoles or flat-bottomed rails to transverse or longitudinal sleepers—first, a spike; second, a headed wood-screw provided with a cotter. The latter has to a great extent superseded the former, being, in fact, in all respects its superior. It is a good attachment, but is not devoid of faults. The conditions required to make it really adequate are that when once screwed in it should never have to

15 be displaced, that the form should afford a surface closely adhering to the foot of the rail. If it be possible to realize these two conditions, the practical result would manifest the following important advantages,

20 namely: facility and economy in maintenance of permanent way, preservation of cross-sleepers and of the foot of the rails, solidity of the Vignoles tracks.

On an examination, in fact, of the functions 30 of the rail-screw it appears at the very outset that as often as it becomes a question of renewing the rail or one of lifting it simply to interpose a sole between the rail and the sleeper, or to renew a chair, it is absolutely necessary to unscrew the rail-screw and disturb its bed. Though it may be restored in exactly the same place and condition it has no longer the same hold, and generally the third time it ceases to bite, necessitating boring 35 a new hole in the sleeper close to the old one, which is filled up with a wooden pin, and so on; but the maintenance of the track so frequently renders such operations necessary that the sleepers very soon suffer, and their 40 preservation in good condition for as long a period as possible has to be considered in relation to their cost. Such is the first and very serious defect of the rail-screw, regarded from the point of view of the direct and movable 45 attachment of the Vignoles rail to the transverse or longitudinal sleeper. The second is perhaps more important, arising, as it does,

from the really inefficient contact of the screw-head with the rail-foot. This contact only takes place on a point, almost on a mere edge, 55 so that it may and not infrequently does happen that the rail-foot slips from its fastening under the pressure of the wheels of the train, especially on curves. Furthermore, this limited point of contact causes it, after some 60 time, to cut into the rail-foot, and consequently to bring about its deterioration.

To obtain a desirable improvement in the means for securing the Vignoles rail, the following conditions must be observed: on the 65 one hand, to preserve the wooden rail-screw by not disturbing it during the raising, arranging, or relaying of the rails; on the other hand, to supplement the limited size and insecurity of the fixed head by the introduction 70 of a part which, although firm and solid in operation, can instantaneously and most easily be dismounted or disconnected, while it broadly and exactly fits the foot of the rail and will secure it to the sleeper with the firmness and solidity of a vise. The arrangements hereinafter described in relation to the accompanying drawings, and which represent the subject of this invention, solve this problem 75 in the simplest possible manner. 80

In the drawings, Figure 1 is a representation of a wooden rail-screw for Vignoles rails, whereof the shank or stem is provided with a collar A at the base of the head. Fig. 2 represents a cleat or clamp arranged to be 85 applied in combination with the rail-screw, Fig. 1. Fig. 3 is a plan of the cleat or clamp, Fig. 2, showing the orifice E to receive the screw-shank formed in the said cleat or clamp and enabling the latter to be fixed by tightening and set free by unscrewing the rail-screw. Fig. 4 is a cross-section showing a 90 Vignoles rail fixed to its transverse sleeper by means of the combination of the two parts shown in Figs. 1, 2, and 3. Fig. 5 is a representation of a slightly-different construction of screw. Fig. 6 shows a slightly-different construction of cleat or clamp, and Fig. 7 a plan view of Fig. 6.

The cleat or clamp, Figs. 2 and 3, rests upon 100 the foot of the Vignoles rail and has one of its sides, C, formed to fit accurately thereto, while the other side, D, rests flat upon the shoulder of the sleeper. The rail-screw pass-

- ing through the aperture E in the cleat, which aperture is larger than the lower extremity of the screw-shank, but entirely covered by the collar A, is screwed down and home into 5 the sleeper. This completes the original laying, as the cleat or clamp is thus rendered immovable by the collar A of the screw, while its point C holds the rail firmly down to the sleeper, as shown at 1, Fig. 4.
- 10 For the purpose of removing the rail it is only necessary to turn the screw about a hitch and a quarter, which raises the collar, releases the cleat at E and C, and then to withdraw the cleat toward the rail, for which the 15 slot or mortise F, communicating with the hole E, is provided, as shown at 2, Fig. 4. Thereafter the rail is free to be raised, removed, and replaced by another without the rail-screws being removed or taken out of 20 their seats.

For relaying the reverse operation is carried out, the cleat being reinserted by means of the mortise F, which passes on both sides of the screw-shank, and the screw is screwed 25 down, which brings it home again and secures the whole.

As a modification of the arrangements above described I will explain that represented in Figs. 5, 6, and 7, wherein the screw-collar A 30 and the shaped or formed screw-hole E in the cleat are omitted. With this arrangement, also, the Vignoles rail can be released without the complete withdrawal of the rail-screws, and in this case the mortise F of the 35 cleat is prolonged of the same width and terminates in the semicircle F' to receive the smooth face F'' of the screw-shank; but these simplified arrangements are far from giving the same security as those illustrated in Figs. 40 1, 2, 3, and 4. In fact, in the case of a possible natural unscrewing or loosening of the rail-screw—such, for instance, from the set-

tling of the sole-plate on which the rail-foot is carried—it may happen that such unscrewing might suffice to allow the cleat or clamp 45 to disengage itself from the rail-screw and separate itself entirely from the rail-foot.

With the arrangement shown in Figs. 1, 2, 3, and 4, on the contrary, by the combined action of the collar A of the rail-screw with 50 the correspondingly-formed orifice E in the cleat the complete separation of the said cleat from the rail could not come to pass before the unscrewing of the rail-screw had raised its collar A out of the formed upper 55 part of E in the cleat.

I claim—

The combination with a sleeper and a rail, of the cleat or clamp having its under surface toward one edge conforming to the shape of 60 the upper face of the base of the rail, said cleat having an aperture E and an open-ended slot communicating with the aperture and extending therefrom to the opposite edge of the cleat, said aperture having a diameter greater 65 than the width of the slot, a headed screw having a shank adapted to pass through the aperture and screw into the sleeper and being also adapted to pass laterally through the slot in the cleat, and a collar on the screw intermediate the shank and the head, said collar adapted to enter the aperture E, and the head on the screw being of larger diameter than said aperture and adapted to rest upon the upper face of the cleat when the screw is 75 screwed down, as specified.

In testimony whereof I have hereunto set my hand in the presence of the two subscribing witnesses.

GEORGES COULON.
